SINGLE-VANED ROTARY DISCHARGE ASSISTANT OPERABLE IN A SIDE OUTLET OF A CONTAINER FOR GRANULAR MATERIAL, AND A WEIGHTED APRON ENGAGING SAID VANE IN ITS OUTERMOST POSITION

Odean Enestvedt, Sacred Heart, Minn.

Application December 12, 1946, Serial No. 715,711

3 Claims. (Cl. 222—410)

1

My invention relates to machines for drying granular material such as corn or the like and has for its primary object the provision of such a machine which is inexpensive in construction and rapid and efficient in its drying action.

Another object of my invention is to provide a structure for the above purpose which both heats and cools the granular material during the drying process so as to place the same in an ideal condition for storage.

Another object of my invention is a novel arrangement of parts whereby the air stream utilized in the cooling of the granular material is thereafter commingled with heated air to heat the granular material as it initially enters the machine.

Another object of my invention is the provision of a novel device for controlling the flow of granular materials from a receptacle containing the same.

The above and still further objects of my invention will become apparent from the following detailed specification, appended claims, and attached drawings.

Referring to the drawings wherein like characters indicate like parts throughout the several views:

Fig. 1 is a side elevation of my machine with some parts broken away and some parts being shown in section;

Fig. 2 is a front elevation of the machine of Fig. 1;

Fig. 3 is a fragmentary section on an enlarged scale taken on the line 3—3 of Fig. 2;

Fig. 4 is a fragmentary section, also on an enlarged scale, taken on the line 4—4 of Fig. 1;

Fig. 5 is a fragmentary section with some parts broken away, taken on the line 5—5 of Fig. 4;

Fig. 6 is a fragmentary vertical section, on a greatly enlarged scale, taken on the line 6—6 of Fig. 2; and

Fig. 7 is a fragmentary view in side elevation taken substantially on the line 7—7 of Fig. 3.

Referring with greater particularity to the drawings, my novel machine is provided with a housing, identified in its entirety by the numeral 1, the upper portion of which defines a material heating chamber 2 and the base of which includes an air heating chamber 3, a blower 4, and a material cooling chamber 5.

Preferably, and as shown, a plurality of reversely inclined perforate conductors or screens 6 are so mounted within the material heating chamber 2 as to provide a continuous cascade for the grain as it passes through the heating cham-

ber 2. These screens are supported and reinforced by angle irons 7. (See particularly Figs. 1 and 2.)

It will be noted that the bottom screen 6 of the cascade is positioned to feed the granular material therefrom into the material cooling chamber 5, which is provided with spaced perforate walls 8 which are substantially parallel.

Secured to the side wall of the air heating chamber 3 is a conventional gun-type electrical oil burner 9, which directs its flame into a refractory bricked fire pot 10. Air heated by the flame from the oil burner, together with the products of combustion, is exhausted from the fire pot 10 and is deflected upwardly by baffle 11 to the blower 4 through an intake passage 12 therein.

As illustrated, particularly in Figs. 3 and 5, cold air is sucked through the spaced perforate sides 8 of material cooling chamber 5 by the fan

10, at which time, it cools the granular material therein. This air then enters the fan housing by way of an opening 13 therein, where it is commingled with the heated air and the products of combustion from the oil burner 9, and is then

15 forced upwardly through outlet passage 14 which terminates at the bottom of the material heating chamber 2. The warmed air is allowed to expand in its upward course through the screens 6 and the granular materials being conducted thereon. At its top, the heating chamber 2 is

20 open to atmosphere. Preferably, and as shown, I also provide a number of fixed cold air openings 15 and a pair of adjustable cold air inlet openings 16 in the air heating chamber 3. However, the number and arrangement of these cold air openings may be varied, as desired.

It will be observed, particularly by reference to Fig. 3, that the perforate walls 8 of the material cooling chamber 5 are relatively closely spaced so as to allow only a thickness of granular material therebetween, through which the cold air may readily pass without too great restriction.

Referring particularly to Figs. 3 and 6, it will be observed that a material receiving and conveying device in the form of a trough and auger 17 and 18 respectively are positioned immediately below a lateral opening 19 adjacent the bottom 20 of material cooling chamber 5. As shown in Fig. 2, trough 17 and auger 18 may, if desired, lead

25 to an elevator mechanism 21 or the like. Positioned in the opening 19 and extending longitudinally thereof is a rotary shaft 22 provided with a radially projecting longitudinally extending vane 23. It will be observed that rotary shaft 22 intersects a plane extending between the top

and bottom edges of the opening 19, the former of which is identified by the numeral 24 and the latter, which is in the form of an outwardly extending lip, identified by the numeral 25. Hinged to the upper edge 24 of opening 19 is a flexible closure flap 26 preferably in the nature of an apron of canvas or some such suitable material. At its bottom edge, the apron 26 is provided with a weight 27, which yieldingly biases the apron in the direction of the rotary shaft 22, and the lip 25 forming the bottom edge of opening 19.

The shaft 22 and radially projecting vane 23 rotate in a clock-like direction in relation to Fig. 6 and feed a predetermined amount of granular material to the trough 17. The speed of shaft 22 determines the rate of feed.

The shaft 22 and the auger 18, as well as the blower 4 and the oil burner 9, are driven from an electric motor 28 through the following connections, to wit: a belt 29 runs over a pulley 30 on the motor 28; a pulley 31 secured to a blower shaft 32, which in turn is connected to the vane 33 of the blower 4; and a pulley 34 in the mechanism of the oil burner 9. An idler pulley 35 serves to keep the belt 29 under proper tension. A chain or belt 36 runs over a pulley 37 on the oil burner mechanism shaft, identified by the numeral 38, and a speed-reducing pulley 39 secured to the end of the auger 18. The shaft 22 is driven from the auger 18 by means of a belt 40 running over a pair of cone pulleys 41, one each on the auger 18 and the shaft 22. Speed of the shaft 22 may be varied by positioning the belt 40 on different steps of the coned pulleys 41.

While I have disclosed a commercial embodiment of my invention, it should be clear that the same is subject to alteration and modification without departure from the scope of the appended claims.

What I claim is:

1. Means for controlling the flow of granular materials from a container having a discharge

opening in the side thereof, said means comprising a horizontally disposed rotary shaft disposed in said opening with its axis parallel to the plane of said opening, said plane intersecting the cross section of said shaft in such a manner that a portion of said cross section extends outwardly beyond said plane, a single radially projecting longitudinally extending vane on said shaft, a longitudinally extended lip projecting laterally outwardly from the bottom of said opening, and a flexible apron hinged to the upper edge of said opening and yieldingly biased toward engagement with said shaft and the extended edge of said lip, said lip projecting laterally outwardly from said plane a distance at least equal to the portion of said shaft outwardly of said plane.

2. The structure defined in claim 1 in which said lip projects laterally outwardly a lesser distance than said vane when said vane is brought to a position overlying said lip.

3. The structure defined in claim 1 in which said apron is biased by a weight secured to the bottom thereof.

ODEAN ENESTVEDT.
